UNITED STATES PATENT OFFICE.

WILLIAM J. KNOX, OF DUBOIS, PENNSYLVANIA, ASSIGNOR TO WALTER P. MURPHY,
OF CHICAGO, ILLINOIS.

UNCOUPLING ATTACHMENT.

1,123,553.

Specification of Letters Patent.

Patented Jan. 5, 1915.

Application filed April 29, 1911. Serial No. 624,176.

To all whom it may concern:

Be it known that I, WILLIAM J. KNOX, a citizen of the United States, residing at Dubois, in the county of Clearfield and 5 State of Pennsylvania, have invented certain new and useful Improvements in Uncoupling Attachments, of which the following is a specification.

The invention relates to uncoupling attachments or rigging for use with the automatic couplers employed upon railway cars.

The primary objects of the invention are: the provision of an improved and positive 15 form of flexible connection wherein the use of chains, loose links and similar devices is avoided; the provision of an uncoupling device capable of use with the brackets now employed with old and unsatisfactory forms 20 of rigging; the provision of an uncoupling device which may be formed of common bar iron or steel so simply manufactured and assembled that highly skilled labor is not required; and the provision of apparatus in 25 which the rigging may be detached from the coupler without detaching the brackets carrying the rigging.

Certain embodiments of the invention are illustrated in the accompanying drawings, wherein:—

Figure 1 is a plan view of the attachment as applied to a car; Fig. 2 is an end elevation of the apparatus as shown in Fig. 1; Fig. 3 is a perspective view of the operating 35 rod employed in Figs. 1 and 2; Figs. 4, 5, and 6 are detail views of a modified form of operating rod; Fig. 7 is a plan view of another form of the apparatus as applied to a car; Fig. 8 is a side elevation of the attachment shown in Fig. 7; Fig. 9 is a section through the rock shaft of Fig. 7 and shows an end elevation of the operating rod shown in such figure; Figs. 10 and 11 are plan and side elevation views respectively 45 of another embodiment of the invention.

Referring to Figs. 1, 2 and 3, 1 is the coupler head, provided with usual vertically movable pin 2; 3 is what may be termed the operating rod; 4 is what may be termed 50 the rock shaft; and 5 and 6 are brackets upon the end of the car for supporting the rock shaft. The end of the operating rod 3 extends slidably through the head of the pin 2 and is provided with a bend 7 for preventing the accidental detachment of the

rod from the pin. The other end of the operating rod is bent at 8 and is provided with a loop 9 encircling the end of the arm 10 of the rock shaft, such arm 10 being provided with a bend 11 at the point of engagement with the loop 9. The arm 10 bends down below the plane of the body of the rock shaft 4 as indicated in Fig. 2, the bend 11 and extreme end of the rock shaft lying below the rod 3. The other end of 60 the rock shaft 4 is provided with the usual handle 12. The rotation of the shaft 4 lifts the end of the arm 10, and because of the loop connection and the fact that the end of the arm 10 passes under the rod 3, such 65 rod 3 is raised, thereby lifting the pin 2. The arrangement provides for a positive connection between the rock shaft and operating rod, and at the same time provides a connection which is entirely flexible, the 70 connection between the loop 9 and bend 11 giving substantially a universal joint. The rod 3 slides freely through the pin 2, so that the coupler head can move a considerable distance in any direction without causing 75 any strain upon the uncoupler rigging or without binding in any way. The bend 11 prevents the loop 9 from slipping off the arm 10 endwise. It will be seen that the construction is a simple one, and one 80 85 that may be readily formed without machine work, from ordinary bar iron. If desired, the shaft 4 may be extended so as to be operable from the other side of the car.

In order to permit the ready removal of 90 the operating rod from the rock shaft, the arrangement shown in Figs. 4, 5 and 6 is preferably used, the only difference of construction in the operating rod 3' there used over that of the operating rod 3 of Figs. 1 and 95 2 being in the fact that the loop 9' is made readily detachably by leaving it open at one side, as indicated in Figs. 5 and 6, and providing a removable cotter pin 13 for closing such open side. It will be seen that this 100 constitutes a cheap and convenient means for providing a detachable connection, so that the operating rod may be disengaged when it is desired to remove the coupler head, such arrangement obviating the necessity of providing for the removal of the rock shaft 4.

A somewhat different arrangement is shown in Figs. 7, 8 and 9. In this construction the operating rod 14 is provided 110

with an open sided loop 15 closed by the cotter pin 16, and this loop engages a bend 17 in the rock shaft 18, the end of such rock shaft crossing the operating rod 14 as in the form of device previously described.

The advantages of this form of construction are substantially the same as those pointed out with respect to the construction shown in Figs. 1 to 6.

10 In Figs. 10 and 11 still another form of construction is shown, operating rod 19 being bent at 20 in the reverse direction and provided with a loop 21 engaging the upturned end 22 of the rock shaft 23. This arrangement also provides for free relative movement between the operating rod and rock shaft, and yet prevents the accidental disengagement of the two members.

Having thus described my invention and 20 illustrated its use, what I claim as new and desire to secure by Letters Patent is the following:

1. An uncoupling attachment comprising an operating rod having one leg extending 25 slidably through the head of the pin and the other leg bent at an angle to such first leg, and provided with a loop, and a rock

shaft having its body portion supported for rotary movement and having one end bent substantially right angles to the body portion and crossing the operating rod, the rock shaft being provided adjacent its end with a bend engaged by the said loop in the operating rod.

2. An uncoupling attachment, comprising 35 a rock shaft having its inner portion bent laterally and such inner portion provided with a bend adjacent its end, an operating rod having one end extending slidably through the head of the pin and the other 40 end bent laterally in substantially a horizontal plane with an open sided loop at its extremity embracing the said bend in the rock shaft, and a removable pin for closing the side of the said loop, the inner end of 45 the said rock shaft being positioned so as to engage the operating rod and lift it.

In testimony whereof I have hereunto signed my name in the presence of the two subscribed witnesses.

WM. J. KNOX.
